UNITED STATES PATENT OFFICE.

HECTOR MARSHALL, OF PORT MELBOURNE, VICTORIA.

WELT-GUIDE FOR SEWING-MACHINES.

SPECIFICATION forming part of Letters Patent No. 673,719, dated May 7, 1901.

Application filed August 18, 1900. Serial No. 27,309. (No model.)

To all whom it may concern:

Be it known that I, HECTOR MARSHALL, boot and shoe architect, a subject of the Queen of Great Britain and Ireland, residing 5 at 227 Bay street, Port Melbourne, in the county of Bourke, Colony of Victoria, have invented certain new and useful Improvements in Welt-Guides for Sewing-Machines, of which the following is a specification.

10 The object of my invention is to provide an attachment for boot and shoe sewing machines whereby the welt-strip may be guided and stitched to the upper and the insole. In the past it has frequently been the practice 15 in the manufacture of boots and shoes first to "pull over" the upper onto the insole on the last, then to place the upper, insole, and last in a lasting-machine, which further strained the upper over and tacked it. Then by hand 20 the upper was "braced" or stitched preparatory to its being placed in the welting-machine, which stitched the upper, the welt, and the insole together; but with my invention the upper is pulled over the toe only of the 25 last, and three or more club-headed tacks withdrawable by hand are driven in. Then without passing through the lasting-machine the upper, insole, and last are placed in front of an ordinary sewing-machine, (having a vertical straight needle,) to which my welt-guiding attachment is affixed.

30 My invention consists of a welt-strip guide, as hereinafter described, secured to the rest of a straight-needle ordinary boot and shoe sewing machine. By it the welt-strip is led 35 into the machine and secured to the insole and the upper, and thereby wetted and lasted in the one operation. A thrust step or shoulder protrudes above the bottom of the welt- 40 guiding hole, and a means is provided for adjusting said hole to varying widths of welt.

Referring to the drawings which form a part of this specification, Figure 1 represents a front view of a sewing-machine with my attachment in place. An arrow shows where the welt enters, and the needle, almost at the top of its stroke, is visible above the needle-hole. The awl is also in view. The width-adjusting piece is removed. Fig. 2 shows a perspective view of my guide detached from the rest and looked at from above it. The arrow indicates the direction of the entering

welt-strip. Fig. 3 represents a perspective view of the guide looked at from the end where the welt-strip enters the welt-strip 55 hole. The adjusting-piece, by which the said hole is made to accommodate welts of different widths, is clearly seen. Fig. 4 shows a view of the width-adjusting piece, which is inserted in the welt-strip-guiding hole. Fig. 60 5 represents a perspective view of a short piece of the welt-strip.

Similar letters of reference indicate similar or corresponding parts where they occur in the several views.

On reference to the drawings it will be seen that a holder A of any section is secured by screws, bolts, studs, or other means to (or it may be part of) the rest B. Integral with the holder or attached thereto is the extension or 70 head C. Penetrating this extension is the elongated needle-hole D. Through this hole passes the needle L, above which is the awl K. A thrust step or shoulder E (against which the boot can be thrust while being 75 sewed) traverses the upper face of the extension, and passing from the top of this step across the extension is the sheet-metal bridge-piece F. One side of this bridge-piece rests upon and is secured to the top of the step or 80 shoulder E and the other (by a flange J) is secured to the side of the extension. The bridge-piece is attached to the extension by screws or other means and forms with the 85 said extension the walls of the hole through which the welt-strip passes. Inside the welt-strip-guiding hole H (see Fig. 3) in the guide is a width-adjusting piece G. This, which is locked in place in any convenient manner, can be removed at will and replaced by those 90 of other size.

I do not bind myself to the particular means described of adjusting the width of the welt-strip hole in the guide, since the making-up pieces may be dispensed with and other means 95 adopted to effect this adjustment.

The cycle of operations is as follows: The leading end of a welt-strip of the desired width having been entered into the guide the said end is so far pushed through that the 100 needle-point will pierce it. The embryo boot (the upper of which has been pulled over and locked by finger-withdrawal tacks) is then placed above the needle. Thus after the awl

penetrates the three plies of material and as the boot travels around in front of the needle the tacks before referred to are removed by the operator and dropped into a tray. The 5 operation is performed not only with ease, but also with both accuracy and despatch, and a joint is made which is absolutely perfect in every particular.

Having now described my invention, what 10 I claim as new, and desire to secure by Letters Patent, is—

1. A welt-strip guide consisting of a holder, having a curved extension or head at one end, a needle-hole through said head, a thrust step 15 or shoulder extending beside and beyond said hole, and a bridge having one end securely fastened to the said step and the other end securely fastened to the opposite side of the head and forming with the opposed faces of 20 the head a welt-guide opening in advance of the needle-opening, all as and for the purposes described.

2. The herein-described welt-strip guide attachment for boot and shoe sewing machines consisting of a curved head having a thrust 25 step or shoulder, a needle-opening through the head and beside the step, a bent bridge in front of the needle-opening having one end directly secured to the step and its other end fastened to the opposite side of the head, said bridge forming with the opposed faces of the head a welt-strip-guiding hole and a removable and interchangeable adjusting-piece 30 fitted in said welt-guide hole at the side opposite the step, for the purpose and substantially as described.

In witness whereof I have hereunto set my hand to this specification in the presence of two witnesses.

HECTOR MARSHALL.
